UNITED STATES PATENT OFFICE.

ALBERT COOK, OF HOLYOKE, MASSACHUSETTS.

BAND-TYING GAUGE.

Application filed December 10, 1921. Serial No. 521,434.

To all whom it may concern:

Be it known that I, ALBERT COOK, a citizen of the United States, and resident of Holyoke, in the county of Hampden and 5 State of Massachusetts, have invented certain new and useful Improvements in Band-Tying Gauges, of which the following is a specification.

This invention relates to improvements 10 in gauges for use in tying driving bands, of band-driven machines, with a regulated tension, the improved device being especially adapted for use in tying the spindle driving bands of spinning or twisting frames.

15 The invention has for its object to provide a simple and durable device of the character set forth so constructed as to decrease the labor and time required in tying bands.

20 In the drawings Fig. 1 is a side elevation of the device attached to a spindle bearing and spindle rail ready for use;

Fig. 2 a similar view showing the pivoted tension controlling member in locked position;

Fig. 3 a vertical sectional view of the device on the line 3—3 of Fig. 4, the band throw-off lever being shown tripped;

Fig. 4 a plan view of the device, the 30 parts being in the position shown in Fig. 2, the whorl guards and the spindle bearing being shown in section;

Figs. 5 and 6 end elevations respectively of the outer and inner faces of the device;

35 Fig. 7 a detail sectional view showing the device for locking the tension regulating member; and

Figs. 8 and 9 diagrammatic views illustrating the tying of a band.

40 The device comprises an attachment and positioning member 1 which is slotted at its lower end and provided with lugs 2 at the opposite vertical sides of the slot. Between these lugs the lower end of a swinging

45 tension-regulating member 3 is pivotally held by a suitable pivot pin 4. A horizontal bracket 5 is carried by the member 1 near its lower end, said bracket being on the opposite side of the member 1 from the ten-

50 sion member and adapted to extend under the spindle rail. The bracket 5 is formed with two lugs 6 which extend through the slot in the member 1 and are secured in position by the pivot pin 4. The lugs 6 snugly fit the slot so that there can be no free up-

and-down-movement of the bracket 5 independently of the member 1. The bracket 5 is provided with an elongated aperture 7 adapted to receive the lower end of a spindle bearing or bolster 8 which depends from the 60 rail 9 of the spinning frame. The aperture 7 is preferably of the same width transversely as the diameter of the spindle bearing, but has considerably greater length to facilitate its engagement with the bearing 65 when the device is in position for use.

The tension member 3 is formed with an extension or abutment 10 at its lower end which is adapted to engage the upper wall of the slot in the member 1 between the lugs 70 6 and to serve as a stop to limit the outward and downward swinging movement of the tension member away from the support or positioning member 1. The tension member 3 is mounted on the pivot 4 between the lugs 75 6, as clearly shown in Fig. 5. The tension member 3 is normally swung away from the support or positioning member 1, to the limit of the movement permitted by the lug 10, by a tension-regulating spring 11. One 80

end of this spring is confined in a socket 12 formed in the member 1, and the other end thereof is confined in a socket 13 formed in an externally threaded plug or nut 14 screwed into the outer end of a cylindrical 85 bore or passage 15 extending through extension member 3, said bore or passage being formed in a cylindrical enlargement 16 of said member. The nut 14 is provided with an interior angular, longitudinally-extending projection 17 which is adapted to be engaged by a wrench for adjusting the nut to vary the tension of the spring 11. Said wrench must be inserted through an aperture in the member 1 and longitudinally 90 through the spring and passage 15.

The member 1 is provided intermediate its ends and on its inner face, that is to say, on the face which is placed next to the rail of the spinning frame, with a rotatable adapter 100 18. This adapter is provided with straight bearing faces 19 and 20, said faces being at right angles to each other and located different distances from the center of the pivot of the adapter. The adapter is formed with two stop shoulders 21 and 22 which are designed to engage a stop in 23 mounted in the member 1. The adapter is also provided with two inwardly extending pins 24, said pins being aligned with the face 19. The 110

the tying device. The plate 30 is formed with longitudinal side flanges 34 which serve to stiffen and straighten said plate. 40

The upper surface of the bracket 26 is cut away on each side to form the horizontal shoulders 35 directly below the plate 30. Secured to each side of the bracket 26, by means of screws 36 and bearing on the shoulders 35, is a spring side arm 37. The free ends of these side arms are bent inwardly 45 toward each other and then back upon themselves to form triangular gripping jaws 38. These jaws are adapted to be forced over the spindle bearing and to yieldingly engage it in order to hold the tying device in position. 50

The member 3 is provided at its upper end with an arm 39 carrying at its inner or free end an upwardly extending tying hook 40 around which the spindle driving band is 55 passed in the operation of tying the band, as indicated in Figs. 8 and 9. The free end of the arm 39 is beveled outwardly and downwardly to form a cam surface 41 adapted to engage and ride over the upper end 60 of a vertically slideable latch 42 and to depress said latch against the pressure of springs 43 when the member 3 is swung toward member 1. The arm 39 is provided with a locking shoulder 44 which is adapted to snap back of the latch bar 42 to lock the tension member 3 against movement after the same is swung a predetermined distance toward the spindle. The latch 42 is confined 65 in a channel formed in the member 1; and the springs 43 are mounted in sockets in said member, as shown in Fig. 7. A pin 45 mounted in member 1 and engaging in a slot 46 in the latch bar 42 serves to limit the movement of said bar. The latch bar 42 at 70 its upper end is provided with two outwardly extending finger pieces 47, one on each side of the arm 39, and said finger pieces are adapted to be depressed by the operator when he desires to release the tension member from the latch 42. 75

A sheet metal cast-off angle lever, or doffer, 48 is pivoted by a pin 49 to the upper end of the tension member. One arm 48^a of said angle lever lies along the upper surface of the tension member, while the other extends downwardly and outwardly by the side of said lever. The upper portion of said arm is cut out at its free end to provide cast-off lugs 50 which lie on either side of the tying hook 40. On the upper member 48^a of the cast-off lever and on each side edge thereof is formed an upwardly extending outwardly projecting guide and retaining hook 51. These hooks are about midway the ends of the upper arm of the cast-off lever and are at each side of the tying hook. The purpose of these retaining and guiding hooks is to hold the band 80 on the tying hook during the operation of 85

pulling the ends of the band in order to place the proper tension on the band. In Fig. 8 the operation of these retaining and guiding hooks 51 is illustrated. Spindle 5 driving bands are usually formed of two strands twisted together. A loop is formed at one end and at the other end the two strands are separated. One of these separated ends is passed through the said loop 10 in one direction and the other is passed through the loop in the opposite direction when it is desired to tie the band to the spindle. As shown in Fig. 8, the separated strands, after they have been passed through 15 the loop in the end of the band, are passed outwardly in opposite directions under the guiding and retaining hooks 51. It is manifest that these hooks serve to hold the band down on the tying hook 40 and prevent it 20 sliding off said hook during the operation of tying the band.

The operation of tying the band is as follows:

The lower end of the spindle bearing 8 25 is engaged in the aperture 7 of the bracket 5, and the member 1 is then swung upwardly to bring its inner face into engagement with the spindle rail 9 and to cause the spring jaws 38 to engage the spindle bearing 28. The recess 27 of the bracket 26 and the recess 31 of the plate 30 receive the spindle bearing and all of these parts serve to center the member 1 properly and to hold it against the spindle rail. The 30 35 tension member 3 is free of the latch 42 and the spring 11 forces it forwardly, that is to say, toward the operator, and downwardly to the limit of its movement. The lug 10 serves as a limit stop. The spindle driving band is then passed around the drive pulley or cylinder and on opposite sides of the spindle whorl and its ends brought together in front of the tying lug 40. One strand of the band is passed 40 45 through the end loop of the band in one direction and the other strand is passed through said loop in the opposite direction. These separated strands are then passed laterally in opposite directions under the retaining hooks 51. The operator then pulls outwardly on the said strands. This causes the strands to bear strongly against the hooks and causes the loop end of the band to engage the tying hook. It will be understood that as strain is put on the separated strands they are pulled out or unravelled from the main body of the band. This 50 55 shortens the band and puts a strain on the tying lug which throws the tension member upwardly and toward the spindle. It sometimes occurs that the looped end of the band will remain between the retaining lugs or hooks during the tying operation and will not engage the tying lug. In this 60 65 event the strain of the strands on the re-

taining lugs will force the tension member upwardly to its latched position and the looped end of the band will engage the tying lug when the strain on the two strands is relieved. The amount of tension required 70 to throw the tension member to its latched position will depend upon the adjustment of the spring 11. When the band has been contracted sufficiently to place the desired amount of tension on the tension member, 75 said member will have been swung upwardly to its latched position, as illustrated in Fig. 3. This takes the tension of spring 11 off the band and the knot may then be completed by tying the two strands together as 80 indicated in Fig. 9. The tying of the band is then completed and by forcing the depending arm of the doffer lever toward the member 3, the cast-off lugs 50 will lift the tied band off the tying lug and allow 85 it to drop between the flanges of the spindle whorl. The guard lugs 33 prevent the band drawing down under the whorl during the tying operation and also prevent the whorl and spindle being lifted during the tying 90 operation. Without the guards 33 it was found that sometimes during the tying operation the band would slip under the whorl. As ordinarily mounted, the spindle has a slight vertical play and sometimes the 95 whorl and spindle were lifted during the tying operation and this resulted in the band slipping under the whorl.

When the tying operation is completed and the band has been released from the tying lug, the latch plate 42 is depressed and the tension member thereby released. The device may then be quickly removed from the spindle. Of course, the device may be removed from the spindle without releasing the tension member, but it is the usual practice to release the tension member and to allow the kick, produced by the tension member flying outwardly, to release the device from the spindle.

What I claim is:

1. A device of the class set forth comprising an attachment member, means carried thereby to engage a spindle bearing support, a movable band-engaging and tensioning member yieldingly held to the attachment member, guards carried by the attachment member and adapted to engage the spindle whorl, and means for locking the tension member when the desired tension has been placed on the band during the tying operation.

2. A band tying gauge comprising an attachment member, means carried thereby to engage a spindle support, a movable band-engaging and tensioning member yieldingly held to the attachment member and provided with a band tying lug to engage the band during the tying operation, and retaining devices carried by said tension mem-

- ber and adapted to be engaged by the strands of the band during the tying operation and serving to hold the band on the band tying lug.
5. A band tying gauge comprising an attachment member, means carried thereby to engage a spindle support, a movable band-engaging and tensioning member yieldingly held to the attachment member and provided with a band tying lug to engage the band during the tying operation, and retaining hooks carried by said tension member and adapted to be engaged by the separated strands of the band during the tying operation and serving to hold the band on the band tying lug.
10. 6. A band tying gauge comprising an attachment member, means carried thereby to engage a spindle support, a movable band-engaging and tensioning member yieldingly held to the attachment member and provided with a band tying lug to engage the band during the tying operation, and retaining means carried by the said tension member and adapted to be engaged by the separated strands of the band during the tying operation and serving to hold the band on the band tying lug.
15. 7. A band tying gauge comprising an attachment member, means carried thereby to engage a spindle support, a movable band-engaging and tensioning member yieldingly held to the attachment member and provided with a band tying lug to engage the band during the tying operation, and a retaining hook carried by the tension member and adapted to be engaged by one of the separated strands of the band to hold the band on the band tying lug during the tying operation.
20. 8. A band tying gauge comprising an attachment member, means carried thereby to engage a spindle support, a movable band-engaging and tensioning member yieldingly held to the attachment member and provided with a band tying lug to engage the band during the tying operation, a cast-off lever pivoted on the tension member and having one arm adapted to detach the tied band from the tying lug, and a pair of retaining devices carried by said arm of the cast-off lever and adapted to be engaged by the strands of the driving band during the tying operation to hold the band on the band tying lug.
25. 9. A band tying gauge comprising an attachment member, means carried thereby to engage a spindle support, a band-engaging and tensioning member yieldingly held to the attachment member and provided with a band tying lug to engage the band during the tying operation, a cast-off lever pivoted on the tension member and having one arm adapted to detach the tied band from the tying lug, and a pair of retaining hooks carried by said arm of the cast-off lever and adapted to be engaged by the strands of the driving band during the tying operation to hold the band on the band tying lug.
30. 10. A device of the class set forth comprising an attachment member, means carried thereby to engage a spindle bearing, adjustable means carried thereby to adapt the device for use on spindle rails of different thicknesses, a movable band engaging and tensioning member yieldingly held to the attachment member, means on the tension member for holding the band during the tying operation, and means for locking the tension member when the desired tension has been placed on the band during the tying operation.
35. 11. A device of the class set forth comprising an attachment member, means carried thereby to engage a spindle bearing, rotatable means carried thereby to adapt the device for use on spindle rails of different thicknesses, a movable band engaging and tensioning member yieldingly held to the attachment member, means on the tension member for holding the band during the tying operation, and means for locking the tension member when the desired tension has been placed on the band during the tying operation.
40. 12. A band tying gauge comprising an attachment member, means carried thereby to engage a spindle support, a band-engaging and tensioning member yieldingly held to the attachment member and provided with a band tying lug to engage the band during the tying operation, a cast-off lever pivoted on the tension member and having one arm adapted to detach the tied band from the
45. 55. 60. 65. 70. 75. 80. 85. 90. 95. 100. 105. 110. 115. 120. 125. 130.

tying lug, and retaining devices carried by the cast-off lever and against which the separated strands may be drawn to place the desired tension on the band to contract it and move the tension member toward the spindle the said retaining device being adapted to hold the band on the tying lug during the tying operation.

8. A band tying gauge comprising an attachment member, means carried thereby to engage a spindle support, a band-engaging and tensioning member yieldingly held to the attachment member and provided with a band tying lug to engage the band during the tying operation, a cast-off lever pivoted on the tension member and having one arm adapted to detach the tied band from the tying lug, and a pair of retaining devices carried by said arm of the cast-off lever and adapted to be engaged by the strands of the driving band during the tying operation to hold the band on the band tying lug.

9. A band tying gauge comprising an attachment member, means carried thereby to engage a spindle support, a band-engaging and tensioning member yieldingly held to the attachment member and provided with a band tying lug to engage the band during the tying operation, a cast-off lever pivoted on the tension member and having one arm adapted to detach the tied band from the tying lug, and a pair of retaining hooks carried by said arm of the cast-off lever and adapted to be engaged by the strands of the driving band during the tying operation to hold the band on the band tying lug.

10. A device of the class set forth comprising an attachment member, means carried thereby to engage a spindle bearing, adjustable means carried thereby to adapt the device for use on spindle rails of different thicknesses, a movable band engaging and tensioning member yieldingly held to the attachment member, means on the tension member for holding the band during the tying operation, and means for locking the tension member when the desired tension has been placed on the band during the tying operation.

11. A device of the class set forth comprising an attachment member, means carried thereby to engage a spindle bearing, rotatable means carried thereby to adapt the device for use on spindle rails of different thicknesses, a movable band engaging and tensioning member yieldingly held to the attachment member, means on the tension member for holding the band during the tying operation, and means for locking the tension member when the desired tension has been placed on the band during the tying operation.

12. A band tying gauge comprising an attachment member, means carried thereby to engage a spindle support, a movable band

engaging and tensioning member yieldingly held to the attachment member, means carried by the attachment member and adapted to engage the spindle whorl to hold it 5 against vertical movement with respect to the attachment member, and means for locking the tension member when the desired tension has been placed on the band during the tying operation.

10 13. A band tying gauge comprising an attachment member, means carried thereby to engage a spindle support, a movable band engaging and tensioning member yieldingly held to the attachment member, and means 15 carried by the attachment member and adapted to hold the spindle whorl against vertical movement with respect to the attachment member.

14. A band tying gauge comprising an attachment member, means carried thereby to engage a spindle support, a movable band engaging and tensioning member yieldingly held to the attachment member and provided with a band tying lug to engage the band 25 during the tying operation, a shiftable cast-off device mounted on the tension member and adapted to detach the tied band from the tying lug, and two separated upstanding retaining devices carried by the cast-off 30 device spaced from the band tying lug and

between which the knot in the band may be formed and against which the free ends of the strands of the partially tied band may be drawn to place the desired tension on the band to contract it and move the tension member toward the spindle. 35

15. A band tying gauge comprising an attachment member, means carried thereby to engage a spindle support, a movable band engaging and tensioning member yieldingly held to the attachment member and provided with a band tying lug to engage the band during the tying operation, a cast-off lever pivoted on the tension member and having one arm adapted to detach the tied band from the tying lug, and two upstanding retaining hooks carried by the said arm of the cast-off lever spaced from the tying lug and spaced apart laterally of the lever arm to permit the knot in the band to be 40 formed between the said hooks and to permit the free ends of the strands to be drawn in opposite directions against said hooks to place the desired tension on the band to contract it and move the tension member to 45 50 55 toward the spindle.

In testimony whereof I hereunto affix my signature.

ALBERT COOK.
